(57) **CLAIM**

The ornamental design for a lighting control console, as shown.

DESCRIPTION

FIG. 1 is a front perspective view of a lighting control console in accordance with our new design;

FIG. 2 is a front elevation view thereof;

FIG. 3 is a rear elevation view thereof;

FIG. 4 is a right side elevation view thereof;

FIG. 5 is a left side elevation view thereof, for the side opposite that of FIG. 4;

FIG. 6 is a top elevation view thereof; and,

FIG. 7 is a bottom elevation view thereof.

The broken lines shown in the drawings are only provided to illustrate the environment of the design, and form no part of the claimed design.

1 Claim, 7 Drawing Sheets
